UNITED STATES PATENT OFFICE.

CHARLES E. VAWTER, OF PHILADELPHIA, PENNSYLVANIA.

TELEPHONE RECEIVER.

Application filed May 23, 1922. Serial No. 562,962.

To all whom it may concern:

Be it known that I, CHARLES E. VAWTER, a citizen of the United States, residing at Philadelphia, in the county of Philadelphia, 5 State of Pennsylvania, have invented certain new and useful Improvements in Telephone Receivers; and I do hereby declare the following to be a full, clear, and exact description of the invention, such as will enable others skilled in the art to which it appertains to make and use the same.

This invention relates to improvements in telephone receivers and more particularly to that type by means of which the sound 10 is greatly amplified.

The ordinary type of telephone receiver comprises principally an electromagnet, a diaphragm of magnetic material, and a permanent magnet, the diaphragm being supported in close proximity to one of the poles of the electromagnet. The permanent magnet creates an initial magnetic field in the air gap between the pole and the diaphragm. This initial magnetic field is then 15 varied by the voice currents flowing in the coil of the electromagnet, the diaphragm being caused to vibrate by the variable attractive force which is exerted directly upon it thru the air gap. This vibration of the diaphragm produces sound waves which follow closely the undulations of the voice currents.

In making a receiver of the loud speaking type, it is desirable to use a diaphragm of material such as mica, which has better acoustic properties than the ordinary diaphragm of magnetic material. If a non-magnetic diaphragm is used, it must be connected in some manner to a magnetic bar 20 or armature in the field of the electromagnet. The pulsating magnetic field causes the armature to vibrate, which, in turn, makes the diaphragm vibrate.

Various methods of producing diaphragm vibrations of large amplitude have been developed. Link mechanisms have been used, the arrangement being such that a comparatively small movement of the armature will produce a much larger movement of the diaphragm. A typical arrangement consists of an armature pivoted at one end and attached to the diaphragm by a suitable link at the other end. The armature is so situated with respect to the electromagnet that the force is applied near the pivoted end, so that the motion of the end

connected to the diaphragm is of greater amplitude than the motion of the part of the armature adjacent to the electromagnet. In another arrangement, a flexible armature is used; one end of the armature is fixed and the other end is connected to the diaphragm. In still another arrangement an armature is used, one end of which is connected to the diaphragm by a suitable link, the other end being supported by a spring. It is apparent that in these various arrangements, the gain in amplitude is made at the expense of the force exerted by the electromagnet, and consequently the amplification depends upon the strength of the electromagnet.

One object of the present invention is to provide a combination of magnets which will give a maximum force on the armature for a given magnetomotive force.

In the present invention a suitably mounted diaphragm is provided, the diaphragm being connected to an armature preferably in such a manner that the armature is freely suspended. The ends of the armature are adjacent the poles of a magnet which strongly magnetizes the armature. By this arrangement, the armature itself becomes a magnet having poles corresponding to the poles adjacent the ends thereof. A magnet is also provided at each end of the armature. These magnets produce a magnetic field at substantially right angles to the armature and diaphragm. The diaphragm is caused to vibrate by varying the magnetic field which acts upon the armature.

An embodiment of the invention is disclosed in the accompanying drawing in which—

Fig. 1 is a section view of a receiver showing the improved construction; and

Fig. 2 is a section view taken at right angles to the plane of Fig. 1.

Referring to the drawing, a case 1 of ordinary construction is shown, having a cap 2 suitably affixed thereto, as by the screw threaded flange 3. A horn 4 is attached to the cap 2 for directing the sound waves. The diaphragm 5 is secured in place between two rubber rings 6. This diaphragm 5 may be of any suitable material, such as mica, and if desirable, the thickness of the diaphragm may vary from the center to the edge, depending upon the results desired. The armature 7 is fastened to the diaphragm by a suitable connecting mem-

ber or link 8 fixed to the armature and held in place by any suitable means, as by the screw 9 passing through the diaphragm. As shown in the drawing, the link 8 is a single straight member, and neither the link nor the armature is pivoted in any way. The armature 7 which is of magnetic material is preferably rectangular in cross section and of a length substantially greater than its width. The connecting member or link 8 should be made of light material in order to lessen the inertia of the moving parts, and should be of large enough cross section at the point of contact with the diaphragm to brace the armature against longitudinal motion, the armature being freely suspended by the link 8.

A U-shaped magnet 10 having inwardly projecting poles 11 and 11' is fastened to the casing 1 in any suitable manner, as by the screws 12. This U-shaped magnet 10 is so situated with respect to the diaphragm 5 and the armature 7 attached thereto, that the poles 11 and 11' are directly opposite the ends of the armature 7. The U-magnet 10 may be a permanent magnet or it may be an electromagnet having a coil 13 mounted thereon. This coil 13 may carry a direct current, in which case the magnet 10 acts as a strong permanent magnet, or it may carry a varying current, in which case the flux across the gaps between the poles 11 and 11', and the armature 7 will vary with the current.

At the end of the armature 7 adjacent the pole 11 of the U-magnet 10, there is a magnet 14 arranged at substantially right angles to the armature 7 and fastened to the case 1 by a screw 16. The shape of this magnet is shown in Fig. 2. It is preferably made in two parts which may be fastened together in any suitable manner as by the screw 16'. Two coils 17 are shown mounted on the legs of this magnet 14, the coils being preferably connected in series. The number of the coils and their arrangement are immaterial, provided the coils are adapted to produce the necessary magnetomotive force. The two poles 18 and 18' of the magnet 14 are situated on opposite sides of the armature 7 so that air gaps are formed between the poles, and the end of the armature 7, these gaps being large enough so that when the armature is vibrating it does not come in contact with either of the poles 18 and 18'. The flux between these poles passes through the end of the armature at substantially right angles thereto.

At the end of the armature 7 adjacent the pole 11' of the U-magnet 10, there is a second magnet 15 exactly like the magnet 14 described above. This magnet 15 is mounted in the case in the same manner as the magnet 14 and carries two coils 19 in se-

ries, corresponding to the coils 17 of magnet 14. The poles 20 and 20' on opposite sides of the armature 7 are separated therefrom by air gaps corresponding to the gaps at the other end of the armature 7.

It is to be understood that the particular shape of the magnets 14 and 15 is not important and any suitable magnetic structure may be employed.

As mentioned above, the diaphragm is caused to vibrate by varying the magnetic field in the vicinity of the armature in such a manner that forces are exerted on the armature at right angles thereto. In one form of my invention, the magnet 10 is a permanent magnet. The leads of the coils 13 on this magnet are connected to a source of direct current, or this coil may be dispensed with if the permanent magnetization is strong enough to secure the desired result. The effect of this magnet 10 is to strongly magnetize the armature 7. The leads of the coils 17 and 19 on the magnets 14 and 15 may be directly connected to the line carrying the varying voice current, or they may be connected to the secondary of a transformer in the voice current circuit. If the latter connection is used, the current flowing in the coils 17 and 19 will be an alternating current.

At a certain instant, the current in the coils 17 and 19 will be in the direction to make the pole 18 a south pole, and the pole 18' a north pole as shown in Fig. 1 by the letters S and N respectively. The connection between the coils 17 and 19 is such that at this given instant the pole 20 is a north pole and pole 20' is a south pole. If the magnetization of the permanent magnet 10 is such that the poles 11 and 11' are north and south poles respectively then the magnetization of the armature 7 will be as indicated in Fig. 1, that is, the end of the armature adjacent the north pole 11 will be a south pole and the opposite end a north pole. Thus, with the polarities as indicated in Fig. 1, there will be a force of attraction between the north pole 18' of the electromagnet 14 and the armature, and there will be a force of repulsion between the south pole 18 and the armature. A double force will also act on the armature 7 between the poles 20 and 20' of the electromagnet 15, by virtue of the attraction between the armature and the south pole 20' and the repulsion between the armature and the north pole 20. The net effect is therefore a very strong force acting on the armature to move it towards the poles 18' and 20' and, accordingly, the diaphragm 5 is distended toward the horn 4.

An instant later the direction of the current in the coils 17 and 19 will be changed and the polarity of the magnets 14 and 15 will therefore be reversed. This reverses

the forces acting upon the armature, and the diaphragm is distended in an opposite direction. The magnetization of the armature 7 does not change for the polarity of the U-magnet 10 remains the same.

If the coils 17 and 19 are connected directly to the voice current circuit, then the varying current in these coils is a pulsating direct current, and the polarity of the electromagnets 14 and 15 is not reversed. The flux between the poles of these magnets varies, however, with the pulsations of the current and a series of unidirectional impulses are transmitted to the diaphragm 5, whereby this diaphragm is caused to vibrate.

In another mode of operation, the magnets 14 and 15 are used as permanent magnets, and if the coils 17 and 19 are used, they carry a direct current. The coil 13 on the U-magnet 10 is connected to the voice circuit or to the secondary of a transformer. If alternating current is flowing in the coil 13 of the U-magnet 10, at a certain instant the polarity of the various elements will be as represented in Fig. 1 and the armature will be moved toward the poles 18' and 20'. At a later instant, when the current in the coil is reversed, the polarity of the U-magnet will be reversed and this reverses the polarity of the armature. Since the polarity of the magnets 14 and 15 remains unchanged, the armature will now be forced away from the poles 18' and 20'. This is due to the fact that the end of the armature adjacent the magnet 14 is now a north pole and is therefore repelled by the north pole 18' and attracted by the south pole 18; and the forces at the other end of the armature act in a corresponding manner.

If the coil 13 is connected directly to the voice current circuits, then it carries a pulsating direct current, and the effect is to vary the strength of the poles 11 and 11' and therefore the magnetization of the armature 7 without, however, reversing the polarity of these elements. When the current in the coil 13 is a maximum, the pole strength of the U-magnet 10 and the magnetization of the armature will be maximum, and the force exerted on the armature by the magnets 14 and 15 will also be a maximum. When the current in the coil 13 is a minimum, the poles 11 and 11' will be weak and the force on the weakly magnetized armature will be a minimum. This variation in force on the armature produces the vibrations of the diaphragm.

This invention includes a strongly magnetized armature, freely suspended from a diaphragm and a plurality of magnets arranged so that the flux between the poles of two of the magnets passes through the ends of the armature at substantially right angles thereto. This arrangement is such that a much greater force is exerted on the arma-

ture for a given amount of energy supplied to the electro-magnet, than can be applied by any arrangement of magnets heretofore employed.

It is to be understood that this invention may be applied to telephone transmitters as well as receivers, and, accordingly the invention is not limited in this respect.

It is apparent that the arrangement, size and proportions of the parts may be varied without departing from the principle of the invention which is not confined to the particular embodiments shown and described, but is intended to cover such modifications thereof as fall within the scope of the pending claims.

I claim:

1. A device of the character described comprising a diaphragm, an armature directly connected thereto and freely suspended therefrom, a magnet at each end of said armature for exerting a magnetic force on said armature at right angles thereto, each of said magnets having two poles on opposite sides of the armature, and means separate from said magnet for strongly magnetizing said armature.

2. A device of the character described comprising a diaphragm, an armature connected thereto, a magnet at each end of said armature for exerting a magnetic force on each pole of said armature, each of said magnets having two poles on opposite sides of said armature and means separate from said magnets for strongly magnetizing said armature.

3. A device of the character described comprising a diaphragm, an armature connected thereto, a magnet at each end of said armature for exerting a magnetic force on each pole of said armature, said forces acting to move each end of said armature in the same direction and means separate from said magnets for strongly magnetizing said armature.

4. A device of the character described comprising a diaphragm, an armature directly connected to said diaphragm and freely suspended therefrom, a magnet for producing a strong constant magnetization of said armature, and a magnet at each end of said armature and having two poles on opposite sides thereof for producing a magnetic flux passing through each end of said magnetized armature at substantially right angles thereto, whereby said diaphragm is caused to vibrate.

5. A device of the character described comprising a diaphragm, an armature directly connected to said diaphragm and freely suspended therefrom, means at each end of said armature for producing a varying magnetic force on each pole of said armature, said forces acting to move each end of said armature in the same direction,

and a magnet separate from said means, for producing a strong constant magnetization of said armature.

6. A device of the character described, comprising a diaphragm, an armature connected to said diaphragm, an electromagnet at each end of said armature arranged at substantially right angles thereto and having two poles on opposite sides of said armature, the coils of said electromagnet being adapted to carry voice currents for producing a varying magnetic field acting upon the poles of said armature for vibrating said diaphragm, and a magnet for producing a strong magnetization of said armature.

7. A device of the character described comprising a diaphragm, an armature, a single straight link connecting said armature to said diaphragm and freely suspending the armature from the diaphragm, an electromagnet at each end of said armature arranged at substantially right angles thereto and having two poles on opposite sides of said armature, each electromagnet comprising a magnetic core and a coil for carrying varying currents for producing a varying magnetic field acting upon the armature pole adjacent thereto, the coils of

said electromagnets being so connected that the varying magnetic forces acting upon said armature tend to move each end of said armature in the same direction and a magnet for producing a strong magnetization of said armature.

8. A device of the character described comprising a diaphragm, an armature, a single straight link connecting said armature to said diaphragm and freely suspending said armature from the diaphragm, said magnet comprising a magnetic core and a coil for carrying a constant direct current, and an electromagnet at each end of said armature, arranged at substantially right angles thereto, each of said electromagnets comprising a magnetic core and coils for carrying voice currents and having two poles on opposite sides of said armature, the coils of said electromagnets being connected in series in such a manner that the varying magnetic fields produced by the voice currents act in unison to move each end of said armature in the same direction and a magnet for producing a strong magnetization of said armature.

In testimony whereof I affix my signature.

CHARLES E. VAWTER.
